UNITED STATES PATENT OFFICE.

CHARLES VASICA, OF LONG ISLAND CITY, NEW YORK.

TYPE-CASTING APPARATUS

1,216,892.

Specification of Letters Patent. Patented Feb. 20, 1917.

Application filed September 12, 1916. Serial No. 119,653.

To all whom it may concern:

Be it known that I, CHARLES VASICA, a subject of the Emperor of Austria-Hungary, and a resident of Long Island City, borough of Queens, in the county of Queens and State of New York, have invented a new and Improved Type-Casting Apparatus, of which the following is a full, clear, and exact description.

This invention relates to metallurgy and has particular reference to novel apparatus for casting type or analogous devices.

Among the objects of the invention is to provide an easily manipulated apparatus, whereby any block of material of special design, which will be referred to hereinafter under the general term of "type," may be put into position for the formation of a matrix which may be preserved for the making at any desired time of any desired number of duplicate devices precisely like the original.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section on the line 1—1 of Fig. 3, showing application of my apparatus in the casting of a duplicate type in connection with the matrix;

Fig. 2 is an elevation of the same, the cover or casing being removed and the pattern or form holding frame being lowered into horizontal position;

Fig. 3 is a plan view corresponding to Fig. 1, but with the casing removed;

Fig. 4 is a view substantially on the line 4—4 of Fig. 3;

Fig. 5 is a plan view of the pattern showing the manner of securing the matrix;

Fig. 6 is a vertical longitudinal section indicating the relation of the form and type to the metal chamber in the formation of the matrix;

Figs. 7 and 8 are perspective views of a type and a matrix corresponding thereto;

Fig. 9 is a perspective view of my special design of form block, and

Fig. 10 is a detail perspective view showing the manner of assembling the form blocks.

Referring now more particularly to the drawings, I show an apparatus comprising a base 10 upon which a casing 11 is adapted to be placed, said casing having a vertical slot 12 in one end.

Secured upon the base 10 is a melting pot 13 having legs 14, the body of the pot being elevated sufficiently to accommodate a Bunsen burner 15 or its equivalent, the tube of which leads through the slot 12. The body of the melting pot is bored vertically forming a chamber 16 to receive a mass of type metal of any suitable nature and a piston 17 is fitted for reciprocation in said chamber 16. A lever 18 is pivoted at 19 upon upwardly projecting ears 20 secured to the upper end of the chamber body, and a link 21 loosely connected to the lever and the upper end of the piston provides a means whereby the piston may be operated. The melted metal 22 is adapted to be forced upwardly and outwardly through a passageway 23 leading to a restricted mouth 24 at the upper portion of the pot 13. The mouth portion of the pot is faced by a plate 25, the outer surface of which is vertical.

At 26, I show a T-shaped bracket pivoted at 27 upon the base 10 for movement around a horizontal axis parallel to the plane of the face of the plate 25. Said bracket is adapted to be swung outwardly from the body of the melting pot and led substantially horizontal preliminary to the practice of the invention, the arms 26' of the bracket extending at right angles on opposite sides of the main portion of the bracket 26.

28 indicates a plate, shown as rectangular in form and pivoted upon a bolt 29 extending through its center and through the bracket 26. By means of a winged nut 30 or its equivalent, the plate 28 may be clamped in fixed position upon the bracket. Said plate 28 carries on two of its adjacent sides, flange members 31 which may be integral or otherwise rigidly secured thereto, forming a right angle corner, with relation

to which the filling blocks or quads may be operated. The plate 28 is provided along its other two sides with longitudinal slots 32, in which clamping heads 33 are slidably mounted, each head carrying a clamping screw 34, the axes of the screws being perpendicular to each other in practice and in a plane close to the active surface of the plate 28.

One of the important features of my improvement consists of a plurality of form blocks 35, one of which is shown in Fig. 9. I employ practically four of these blocks, all of the same construction. Each block 15 comprises two parts or portions, one of which, 35^a, is longer and thinner than the other, 35^b. The projecting end of the part 35^a of each block takes under a shoulder formed on the next adjacent block arranged 20 at right angles thereto. By this means the blocks 35 all have a sort of interlocking engagement with one another, forming a rectangular space at the center, into which the type T to be reproduced is locked by the 25 application of the binding screws 34 against two adjacent blocks 35, as shown best in Fig. 5. The offset portions of the blocks 35 provide a chamber for the formation of the matrix of larger diameter than the original 30 type. By reference to Figs. 6, 7, and 8, this fact will be appreciated. Fig. 8 indicates the matrix M of larger diameter than the type, the same being formed as shown in Fig. 6, in the enlarged chamber. By this 35 fact, furthermore, a perfectly square shoulder is provided for the end of the type. By comparing Figs. 1 and 6, it will be noted that the form blocks 35 are reversed according to the product to be molded. They are 40 arranged, first, with the smaller caliber of chamber adjacent to the plate 28 for the formation of the matrix and afterward in holding the matrix for reproduction of the type, the larger caliber of chamber is next to the 45 plate 28. The action of the clamping screws, however, is the same in both cases. Any suitable number or size of quads Q may be used to properly position the form blocks with respect to the plate 28, so as to bring the type 50 chamber in registry with the mouth 24 when the bracket 26 is swung into vertical position bringing the outer edges of the form blocks squarely against the face of the plate 25. In this position, the plate 28 and parts 55 carried thereby are positively locked by means of a yoke 36 pivoted at 37 on opposite sides of the body of the melting pot. Said yoke is formed with notches 38 which take over the upper edges of the laterally projecting arms 26'.

From the above detailed description of the mechanism, its construction or manner of use may be briefly summarized as follows: Given any type T to be reproduced 60 or to be provided with a matrix for future

reproduction of the type, said type is put into the position indicated in Fig. 6 and the platen swung to its upright position, as shown in Fig. 1. With the casing 12 in place and the apparatus properly heated to permit of the passing of the molten metal 22 out through the passageway 23, the matrix then will be formed in the space, as indicated in Fig. 6. Any suitable coating, of course, may be placed upon the surface of the type to prevent the matrix from sticking thereto. After the matrix is formed in this manner and solidified, the operator will loosen the nut 30 to permit the rotation of the plate around the axis of the bolt 29, whereby the comparatively thin neck of metal at the mouth 24 will be sheared off of the matrix by means of the plate 25. This expedient prevents any possibility of distortion of the edges of the matrix where they coöperate with the type which might otherwise be incident to the separation of the type and matrix. After the form blocks are loosened, however, the type and matrix may be separated with impunity with the exercise of ordinary care. The matrix thus formed may be kept any length of time and may always be used in the manner indicated herein for the formation of any number of type precisely similar to the original by an 90 operation similar to that above described and indicated in Fig. 1.

I claim:

1. In type casting apparatus, a melting pot having a delivery passageway leading through the body thereof, means to force molten metal therethrough, a face plate having a restricted mouth constituting the end of the passageway, a platen, means to clamp form devices on the platen for coöperation with the face of the face plate around said mouth, and means to support the platen and form devices in position to receive the metal delivered through the passageway, said supporting devices including pivot means having an axis perpendicular to the face plate and providing for the rotation of the platen around said axis and the shearing off of the formed metal from the face plate.

2. In a device of the character set forth, the combination with a melting pot having a discharge passageway for the molten metal and means to discharge the molten metal therethrough, of a bracket mounted to swing around a horizontal axis, a plate swiveled to the end of the bracket for rotation around an axis perpendicular to the axis of the bracket, form devices carried by the plate and adapted to be brought thereby into registry with the end of the passageway to receive the molten metal, and means to lock the bracket and devices carried thereby in receiving position.

3. In a device of the character set forth, the combination with a melting pot and

means to deliver molten metal therefrom, of a bracket having laterally projecting cross arms, a plate secured to the bracket adjacent said arms, said plate having rigid flanges 5 secured to two adjacent edges thereof at right angles to each other and to the plate, said plate also having along its remaining two edges longitudinal slots, clamping means adjustable along said slots and movable

toward the opposite flanges, form devices 10 clamped between the clamping device and flanges and movable with the plate and bracket into position to receive the molten metal, and a locking bail coöperating with said arms to hold the bracket and form de- 15 vices in fixed position.

CHARLES VASICA.
